UNITED STATES PATENT OFFICE.

EDWIN H. BELL, OF CHICAGO, ILLINOIS.

TIE PLATE.

Application filed March 8, 1926. Serial No. 93,073.

This invention relates to improvements in tie plates, and more particularly to that type of plates having a plurality of parallel grooves or recesses in the bottom, the flattened, arcuate surfaces of which intersect to form tie engaging ribs, which extend longitudinally of the tie, separating, but not cutting the fibres, and compressing and shaping the top surface of the tie to conform to the contour of the plate. Tie plates of this type are known to the art as "compression bottom" tie plates, and are revealed in my former United States Letters Patent No. 1,219,224, dated March 13, 1917.

The present invention consists in the arrangement and combination of features illustrated, described and more particularly set forth in the claims hereto appended.

In the drawings:

Figure 1 is a top plan view of a tie plate embodying my invention.

Figure 2 is a bottom plan view of the plate.

Figure 3 is a longitudinal, sectional view of the plate, enlarged, the section being taken in the vertical plane indicated by the dotted line 3—3 on Figure 4.

Figure 4 is a transverse, sectional view of the plate, enlarged, the section being taken in the vertical plane indicated by the dotted line 4—4 on Figure 3.

In said drawings, the plate, indicated as a whole by the letter A, is shown as of typical dimensions, and provided on its top with a rail bearing surface 1, which may be of any desired configuration, but is here shown as flat. Upon the top of the plate is a transverse, rail abutting shoulder flange 2. The top of the plate is inclined or canted from the base of this flange 2 towards the inner end of the plate. At each end of the plate, the top surfaces 3 and 4 are also tapered or inclined towards the ends 5 and 6 respectively. 7 indicates spike holes, the number, size and location of which may be varied to suit requirements. The rail bearing surface 1 may also be crowned or cambered if desired, but I have shown it to be flat.

The bottom of the plate is of special configuration for it will be seen to be divided, generally, into two end portions or sections and one intermediate portion, the two end portions 8 and 9 being flat, and the intermediate or "compression" section being formed of a plurality of grooves, recesses and ribs.

These grooves or recesses 10, 10, are parallel, and of such number as to extend from one side to the other side of the plate and longitudinally thereof below the rail bearing surface 1 of the plate top, as shown in Figures 2 and 4. The surface of each recess or groove is of a flattened curve or arc in cross section. At each end of these recesses 10, and extending transversely across the bottom of the plate, are tie penetrating, depending ribs 11, 11, as shown in Figures 2 and 4. These transverse ribs 11, 11, separate the central or compression section from the two end sections 8 and 9.

The arcuate surfaces of the grooves 10 intersect in a plurality of parallel lines in the same plane and thus produce, in effect, a plurality of parallel, longitudinally extending ribs 12. As the plate is forced into the tie, these ribs 12 enter the tie between the fibres, thus separating and compressing, but not cutting, the fibres of the tie.

The arcuate surfaces 10 intersect in a plane below the plane of the end surfaces 8 and 9. This plane may be coincident with the plane of the tips or points of the transverse ribs 11, 11, although as shown herein, it is slightly above said plane. That is to say, when the tie plate is laid upon the top of the tie, indicated in Figure 3 by the dotted line T—T, the plate will first rest upon the points of the ribs 11; the plane of the intersecting surfaces to form ribs 12 will be above the plane of the line T—T, and between the plane of the end surfaces 8 and 9 and the plane of the line T—T. The deepest parts of the grooves 10 will be in a plane still further above the plane of the surfaces 8 and 9.

It is very desirable in tie plates to configure the plate so that it will have the greatest strength where strength is required; will have the maximum of holding power with respect to the tie, and will readily form its own seat in the tie under load. The plate of the present invention has all of these characteristics. When first placed in position upon a tie, as indicated in Figure 3, the ribs 11 readily enter the tie under a very slight tap of a hammer or sledge, which causes the plate to remain in its set position without being shifted by the operation of placing the rail upon the plate, and of spiking the rail and the plate to the tie. The plate thus has what I have chosen to call an "initial" bearing surface, comprising the

plurality of points or ribs 12, as well as the ribs 11, 11.

It will be noted that this initial bearing surface is in the intermediate portion of the bottom of the tie plate and its effect is to initially hold the end surfaces 8 and 9 out of contact with the tie. As the plate is being further seated into the tie by train loads, the act of compressing the fibres of the tie begins and progresses perceptibly before the bottom surfaces 8 and 9 of the plate ends actually contact with the tie. With continuing loads, the plate as a whole is depressed into the tie until finally the entire arcuate surfaces 10 come to an ultimate rest on the tie, the top surface of the tie being compressed and configurated to form a seat for the configurated bottom of the plate. When thus finally seated, the surfaces 8 and 9 of the plate will also be slightly imbedded in the tie below the plane T—T of the top surface.

To lighten a tie plate, metal is usually removed from the median portions of the bottom; that is, the portion below the rail bearing surface 1. When train loads are applied to a tie plate which is in contact at its ends upon the tie, there is a tendency for the plate to bend or buckle, and in some cases to break. Another difficulty heretofore experienced in the seating of tie plates, is due to the resistance caused by the relatively wide, flat end portions of the plate and which are in the plane of the bottom of the plate as a whole. This resistance, in addition to causing buckling, makes it difficult for the recessed or configurated intermediate portion to become properly seated.

In my plate, I find that on account of the non-contact of the end surfaces 8 and 9, due to the "initial" bearing or seating provided, no bending or buckling occurs and that

shaping of the top of the tie to conform to the compression bottom intermediate section of the plate progresses perceptibly and rapidly before the flattened end surfaces 8 and 9 actually contact with the tie, and that these surfaces readily become imbedded. Thus the plate as a whole enters the tie and acquires its ultimate seat. 50

I claim as my invention:

1. A tie plate having on its top a rail bearing surface and a transversely extending rail abutting shoulder, and having on its bottom transversely extending, tie penetrating ribs, a tie bearing surface at each end of the plate outside said ribs, and a plurality of parallel, arcuate, flattened compression grooves extending across the bottom of the plate intermediate the transverse ribs, the surfaces of the grooves intersecting in lines to form longitudinally extending, dividing ribs which initially engage the tie at, or substantially at, the same time that the transverse ribs enter the surface of the tie. 65

2. A tie plate having on its top rail bearing surface and a transversely extending rail abutting shoulder, and having on its bottom transversely extending, tie penetrating ribs, a tie bearing surface at each end of the bottom outside the transverse ribs, a plurality of parallel, arcuate, compression grooves extending longitudinally of the plate intermediate the transverse ribs, the surfaces of the said compression grooves intersecting to form a plurality of dividing ribs extending longitudinally from one transverse rib to the other, the plane of intersection being below the plane of the end portions of the plate. 75 80

In testimony, that I, claim the foregoing as my invention I affix my signature this 5th day of March, 1926.

EDWIN H. BELL.
